(57) **CLAIM**

The ornamental design for a console for exercise equipment, as shown and described.

DESCRIPTION

FIG. 1 is a perspective view of the first embodiment of a console for exercise equipment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the second embodiment of a console for exercise equipment;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The evenly broken line in the drawings depicts unclaimed portion of the console only and the dash-dot broken line discloses boundary of the claim. Broken lines form no part of the claimed design.

1 Claim, 10 Drawing Sheets
